UNITED STATES PATENT OFFICE

JOHN HOWARD ESSICK, OF ERIE, PENNSYLVANIA

CARBON REMOVER

No Drawing.

Application filed April 4, 1931. Serial No. 527,853.

This invention relates to compounds for use in the cylinders of an internal combustion engine for effecting the removing of carbon therefrom.

5 The primary object of the present invention is to provide a carbon remover for internal combustion engines which, when inserted into the engine cylinders, will penetrate to all parts thereof and thoroughly 10 soften the carbon to such a degree that upon the subsequent running of the engine it will be easily dislodged from the cylinder wall and from the piston and expelled through the engine exhaust passages.

15 Another object of the invention is to provide a carbon remover which, in addition to thoroughly softening the carbon, will leave upon the cylinder wall and upon the valve stems of the engine an oil deposit which will 20 lubricate the same.

The composition consists of a mixture of volatile and non-volatile fluids. The composition is inserted into the engine cylinders while the same are in a heated condition so 25 that the volatile fluids thereof will be rapidly vaporized and this vapor or gas will penetrate every part of the chamber and will thoroughly soften the carbon therein. The non-volatile constituents are deposited on 30 the surfaces of the cylinder wall and valve stems and act to lubricate the same.

The composition embodying the present invention consists of the following ingredients combined in the appended approximate proportions for the making of a 50-gallon batch of the product.

	Gallons
Benzol (90 proof)	18 1/2
Acetone (dimethyl ketone)	16 1/2
40. Alcohol (denatured—188 proof)	12
Oil of cedar wood (grade—U. S. P.)	1
Camphorated oil (grade—U. S. P.)	1
Turpentine	1

45 The ingredients enumerated are mixed together in the order given and the composition is ready for use.

The carbon remover is used by inserting the necessary quantity of the same in each 50 of the cylinders of the motor vehicle engine, through the spark plug holes thereof, the in-

sertion of the composition being made while the cylinders are hot. The composition immediately forms a gas through the evaporation of the benzol, acetone, alcohol and the camphor of the camphorated oil which penetrates to all parts of the cylinder and works into the carbon to change it to a pasty condition. The motor is then allowed to stand for approximately twenty minutes with this composition in the cylinders, after which it is 55 started and raced a second at a time for approximately a minute. This operation of the engine causes the carbon to break away from the cylinder walls and from the piston and pass out of the engine through the exhaust 60 ports.

The non-volatile constituents of the composition, such as the cotton seed oil of which the camphorated oil is made, the oil of cedar wood and the turpentine, are deposited on 70 the moving parts of the machine and operate to lubricate the same.

Should the carbon in the engine be badly crystallized several treatments with the composition, in the manner above outlined, may 75 be necessary to soften the carbon to the point where it will leave the cylinder and will not get between the wall of the same and the piston and cause scoring of the cylinder wall.

80 While denatured alcohol has been called for in the formula, it will, of course, be understood that grain or ethyl alcohol may be employed in the pure state or methyl alcohol may also be used if desired.

85 It has been found, as a result of experimentation, that various quantities of the present composition may be employed in the engine cylinders with good results, but it has been found that the best results are obtained 90 through the use of approximately one fluid ounce of the preparation in each cylinder.

Having thus described the invention, what is claimed is:

1. A carbon remover of the character described, consisting of benzol, acetone, alcohol, oil of cedar wood, camphorated oil and turpentine.
2. A carbon remover for internal combustion engines, consisting of the following in-

gredients taken in the appended approximate proportions for the production of a 50-gallon batch:

	Gallons
Benzol (90 proof)	18½
Acetone (dimethyl ketone)	16½
Alcohol (denatured—188 proof)	12
Oil of cedar wood (grade—U. S. P.)	1
Camphorated oil (grade—U. S. P.)	1
Turpentine	1

10 In testimony whereof I hereunto affix my signature.

J. HOWARD ESSICK.
